CLAIM

The ornamental design for a playing surface for spinning top toy, as shown and described.

DESCRIPTION

FIG. 1 is a front elevational view of the playing surface for spinning top toy, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, bottom perspective view thereof;

FIG. 9 is a front, right-side, top disassembled perspective view thereof;

FIG. 10 is a top plan reference view omitting the oblique shading on the transparent parts;

FIG. 11 is a top plan reference view omitting the structure behind the transparent parts;

FIG. 12 is a front, right-side, top perspective reference view omitting the oblique shading on the transparent parts; and,

FIG. 13 is a front, right-side, top perspective reference view omitting the structure behind the transparent parts.
